UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL DISTRIBUTING MECHANISM.

Application filed November 8, 1923. Serial No. 673,421.

This invention relates to typographical machines, such as linotype machines of the general organization represented in U. S. Letters Patent to O. Mergenthaler, No. 436,532, 5 wherein circulating matrices are released from a magazine in the order in which they are to appear in print and then assembled in line, the composed line transferred to the face of a mold, the mold filled with molten metal to form a slug or linotype against the matrices which produce the type characters thereon, and the matrices thereafter returned through a distributing mechanism to the magazine from which they 10 started. In some machines, such as the commercial Model 9, where matrices may be drawn from several magazines and mixed together in the same line, the distributing mechanism includes a primary distributor 15 which first sorts the matrices according to font, and a plurality of main distributors which sort the matrices of the individual fonts according to character and restore them to their proper channels in the magazines. 20

The present improvements are herein shown as applied to a primary distributor, but it should be understood that they are 25 equally applicable to the ordinary character distributor. In either case, the matrices are fed to the distributor through a so-called distributor box equipped with a reciprocating lifting finger which detaches the matrices one at a time from the line and delivers 30 them into engagement with the distributor screws. Ordinarily, the lifting finger is recessed at its upper end to provide a vertical lip or shoulder for engaging the front 35 face of a leading matrix and a horizontal ledge for engaging the bottom edge of said matrix. In order to prevent the detachment 40 of more than one matrix at a time, the horizontal ledge portion of the lifting finger is limited in width to a very small fraction 45 of an inch, or something less than the thickness of the thinnest matrix. As thus constructed, it has been found in practice, the lifting finger sometimes fails to function 50 properly, since there is a tendency for a matrix, particularly one of the thicker variety, to become disengaged from the finger during the lifting action.

It is an object, therefore, of the present invention to provide a lifting finger which will 55 cooperate with matrices of all sizes and de-

liver them to the distributor in the required manner. Accordingly, the lifting finger is so constructed and operated that it will engage the bottom of a leading matrix within the required limitations but, in rising, will gradually increase the extent of such engagement until it reaches the limit of its upward stroke and then continues to support the matrix until the latter is advanced 60 to the proper distance by the distributor screws. 65 The exact construction and mode of operation of the parts will best be understood from the detailed description to follow.

In the accompanying drawings, the invention has been shown merely in preferred 70 form and by way of example and as applied to the specific type of distributor indicated. However, many changes and variations may be made therein and in its mode of application, which will still be comprised within 75 its spirit. It is to be understood, therefore, that the invention is not limited to any specific form or embodiment except in so far as such limitations are specified in the 80 claims.

Referring to the drawings:—

Fig. 1 is an elevation of a primary distributor, partly broken away, and showing the present improvements applied thereto;

Fig. 2 is a transverse section taken on the 85 line 2—2 of Fig. 1;

Fig. 3 is a detail, showing the relation of the parts when a matrix is being lifted into the screws;

Fig. 4 is a detail of the improved lifting 90 finger; and

Fig. 5 is a detail of the operating cam and roller.

As shown in Fig. 1, the primary distributor comprises a longitudinally ribbed bar 95 A, formed at intervals with blank spaces A¹, a set of matrix conveying screws B, and a plurality of font selecting bridges C underlying the blank spaces A¹ and acting to direct the matrices X into one or another of the tubes D leading to the main distributors (not shown). The matrices are delivered one at a time to the primary distributor from a distributor box E into which they 100 are pushed from a second elevator F by a transfer device G. The distributor box is provided with upper and lower rails E¹ which sustain the matrices by their projecting ears X¹ and which are formed at the delivery end of the box with arresting shoul- 110

ders or abutments E^2 against which the matrices are normally pressed by the transfer device. At this point, the distributor box is also equipped with a vertically movable finger H which acts to lift the matrices one at a time into engagement with the distributor screws B . As each matrix is thus lifted, its projecting ears X^1 slide along upwardly inclined portions e of the abutments E^2 and thence along horizontally extending portions e^1 thereof onto the distributor bar A . The matrix lifting finger H is pivotally mounted upon a rocking lever J moved in one direction by a spring K and in the opposite direction by a cam L on one of the distributor screws. The foregoing parts and their mode of operation, except as hereinafter pointed out, are or may be of any approved construction or as embodied in the commercial lino-type machine.

In carrying out the present invention, the matrix lifting finger H , instead of being recessed at its upper end as heretofore, is provided with a broad, flat, shelf-like top H^1 for engagement with the bottom edges only of the matrices X . A spring M , connected at one end to the finger H and at its opposite end to the distributor box E , serves to hold the finger in constant engagement with the flattened and finished face of a stationary transverse block N carried by the distributor box. The purpose of this stationary block N is to locate the lifting finger in proper engaging relation to the successive matrices passing through the distributor box; that is to say, in such position that it cannot engage more than one matrix at a time, and also to guide the lifting finger in a substantially vertical plane during its upward movement. It will now be evident that, as each matrix is lifted by the finger H , a relative movement takes place between the two, as permitted by the flat, shelf-like top H^1 and the upwardly inclined portions e of the rail abutments E^2 . In other words, during its upward movement, a detached matrix is permitted to move forwardly in a horizontal direction without displacement of the lifting finger, the matrix sliding across the shelf-like top H^1 of the lifting finger H as it ascends the inclined portions e of the rail abutments E^2 . In this way, the lifting finger is enabled to cooperate with matrices of all sizes without danger of being disengaged therefrom. As a matter of fact, the extent of engagement between the lifting finger and the successive matrices is actually increased during the lifting stroke, so that the action of the parts is materially improved in all respects.

The width of the shelf-like top H^1 is somewhat greater than the horizontal space occupied by the inclined portions e of the rail abutments E^2 , being great enough to enable the top to give support to each lifted matrix until its projecting ears X^1 pass onto the

horizontally extending portions e^1 of the rail abutments. To give effect to this phase of the invention, the cam L is formed with a concentric portion L^1 which will allow the lifting finger to pause in its raised position for the necessary period. As a result, the danger of matrices lagging behind or falling back into the distributor box is minimized, if not entirely obviated.

Having thus described my invention, its construction and mode of operation, what I claim and desire to secure by Letters Patent of the United States, is as follows:—

1. In a typographical distributing mechanism, the combination of a distributor box through which matrices are advanced for distribution, upper and lower matrix sustaining rails arranged within said box and provided with matrix arresting abutments having upwardly inclined and horizontally extending portions to guide the matrices by their projecting ears, a matrix lifting member mounted to reciprocate in said box and having a flat shelf-like top of a width greater than the horizontal space occupied by said upwardly inclined portions, and stationary locating and guiding means cooperating with said lifting member.

2. In a typographical distributing mechanism, the combination with a primary distributor comprising a distributor bar, a set of matrix conveying screws, and selecting bridges for separating the matrices according to font, of a distributor box through which matrices are advanced for delivery to the screws, a flat-topped matrix lifting member mounted to reciprocate in said box, and stationary locating and guiding means cooperating with said lifting member.

3. In a typographical distributing mechanism, the combination of a distributor box through which matrices are advanced for distribution, upper and lower matrix sustaining rails arranged within said box and provided with matrix arresting abutments having upwardly inclined and horizontally extending portions to guide the matrices by their projecting ears, a matrix lifting member mounted to reciprocate in said box and having a flat shelf-like top of a width greater than the horizontal space occupied by said upwardly inclined portions, and means for actuating the lifting member, said means acting to maintain the lifting member momentarily at rest in its raised position to support the matrices until they have passed onto the horizontally extending portions of the rail abutments.

4. In a typographical distributing mechanism, the combination of a distributor box through which matrices are advanced for distribution, upper and lower matrix sustaining rails arranged within said box and provided with matrix arresting abutments having upwardly inclined and horizontally

extending portions to guide the matrices by their projecting ears, a matrix lifting member mounted to reciprocate in said box and having a flat shelf-like top of a width greater than the horizontal space occupied by said upwardly inclined portions, stationary locating and guiding means cooperating with said lifting member, and means for actuating the lifting member, said means

acting to maintain the lifting member momentarily at rest in its raised position to support the matrices until they have passed onto the horizontally extending portions of the rail abutments. 10

In testimony whereof, I have affixed my 15 signature hereto.

DAVID S. KENNEDY.
